F. SCORDAMAGLIA

ELECTRIC FUSE INDICATOR

Filed March 5, 1926

BY

INVENTOR
Frank Scordamaglia
John H. Schlesinger
ATTORNEY

UNITED STATES PATENT OFFICE.

FRANK SCORDAMAGLIA, OF BROOKLYN, NEW YORK.

ELECTRIC-FUSE INDICATOR.

Application filed March 3, 1926. Serial No. 91,874.

This invention relates to electric fuse indicators, and improvements therein, particularly of the type used in conjunction with cut-out blocks, and the invention has for 5 an object the provision of a novel construction and arrangement of parts, indicating by a glowing lamp that the fuse has blown.

For further comprehension of the invention, and of the objects and advantages 10 thereof, reference will be had to the following description, and accompanying drawing, and to the appended claims in which the various novel features of the invention are more particularly set forth.

15 Referring to the drawing forming a material part of this disclosure:—

Fig. 1 shows a plan elevational view of an ordinary cut-out fuse block, having this invention applied thereto.

20 Fig. 2, shows a transversely sectional view, taken on the line 2—2 of Fig. 1.

Fig. 3 shows a longitudinal sectional view taken on the line 3—3 of Fig. 1.

25 Fig. 4 shows a fragmentary transverse sectional view, similar to Fig. 2, but of a modified construction.

Fig. 5 shows a view, similar to Fig. 4, but of a further modification.

Fig. 6 shows a view, similar to Figs. 4, 30 and 5, but of another modified form.

Fig. 7 shows a transverse sectional view of a modified form of clip, adjustably adapted to hold the fuse, and lamp indicator.

The reference numeral 10, indicates a customary porcelain cut-out fuse block, having countersunk apertures 11, to accommodate screws for fastening to a base, transverse grooves 12, and 13, for power lead wires, and longitudinal chambers 14, and 15, for 35 fuses, or the like. Chamber 14 has clips 16 and 17 supported from the bottom thereof, clip 17 being, connected to a terminal 18, clip 16 to a terminal 19 extending into transverse groove 12, and a customary fuse 20 being inserted between said clips 16, and 17; forming a complete line of a circuit from terminal 19 to 18. Chamber 15 has clips 16' and 17', supported from the bottom thereof, clip 17' being connected to a terminal 18', clip 16' to a terminal 19' extending into transverse groove 13, by means of connection strip 21, in a recess 22, of the block 10, which recess may thereafter be filled with sealing wax, as is customary, and a lamp 23, with 50 auxiliary clips 24, and 25 on the ends being inserted between said clips 16' and 17' re-

spectively. Auxiliary clips 24, and 25, have their upper ends bent over upon themselves, as shown in Fig. 2, to form a double action clip, viz, the outer portions exerting holding pressure against a porcelain insulation member 26 also resting on the side walls of chamber 15, and the inner portions exerting holding pressure against a fuse 27 inserted between said clips 24, and 25, forming a complete line of a circuit from the terminal 19', through the connection 21, the clip 16', clip 24, fuse 27, clip 25, clip 17', and terminal 18', the lamp 23 being of very high resistance, so as to force the current through the 70 path of least resistance, viz, the fuse. But should the fuse 27 blow, for some reason, the current will travel through the lamp 23, making the said lamp glow, and indicating the fact that the fuse has blown.

75 In the modification shown in Fig. 4, the clip 25^a has its uppermost edges bent outward, engaging in a groove 26^a of the porcelain insulation member 26'. In Fig. 5, the chamber 15 has its walls extended, as at 30, 80 to eliminate the necessity of a separate insulation member, to protect the upper fuse, and the clip 17^a is of extended length, accommodating the upper fuse, and eliminating an auxiliary clip, a bolt and nut 31 being 85 provided to clamp the center of the clip. In Fig. 6, a knife blade clip 17^b being provided to co-act with a knife blade fuse 27^a, and a knife blade lamp 23^a, instead of the cartridge fuse and lamp, used in the 90 other embodiments. In Fig. 7, an adjustable clip, to accommodate different diameters of fuses, is shown engaging fuse 27, and lamp 23. This clip is formed with a stationary side 35, fixed in any suitable manner to the bracket, and a movable side 36, formed with an upper movable portion 37, and a lower movable portion 38. The upper movable portion 37 being formed complementary to the upper parts of the stationary side of the clip, and provided with a flange 39, having an elongated aperture 40, through which extends a screw 41, threadedly engaged in an upper flange 42, of the lower portion, and an adjusting stud 43 has an abutting head 44, and is revolvable in the part 37, and threadedly engaged in the part 35. The lower movable portion being formed complementary to the lower part of the stationary side of the clip, and provided with a lower flange 39^a, a holding screw 41^a, 100 and an adjusting stud 43^a, all similarly con-

structed, and operable, as corresponding parts of the upper movable portion 37.

While I have illustrated and described my invention with some degree of particularity, I realize that in practice various alterations therein may be made. I therefore reserve the right and privilege of changing the form of the details of construction, or otherwise altering the arrangement of the correlated parts without departing from the spirit or the scope of the appended claims.

Having thus described my invention what I claim as new and desire to secure by United States Letters Patent, is:—

- 15 1. In a device of the class described, an insulation block formed with a pair of transverse grooves, and a pair of longitudinal chambers, a terminal in one of said transverse grooves, electrically connected to a clip in one of said chambers, engaging one end of a fuse having its other end engaged by another clip electrically connected to a terminal, and a terminal in the other of said transverse grooves electrically connected to a 20 long clip in the other of said chambers, engaging one end each of a fuse and an in-
- 20
- 25

dicating lamp, having their other ends engaged by another long clip electrically connected to another terminal.

2. In a device of the class described, an insulation block formed with a pair of transverse grooves, and a pair of longitudinal chambers, a terminal in one of said transverse grooves, electrically connected to a clip in one of said chambers, engaging one end of a fuse having its other end engaged by another clip electrically connected to a terminal, a terminal in the other of said transverse grooves, electrically connected to a long clip in the other of said chambers, engaging one end each of a fuse and an indicating lamp, having their other ends engaged by another long clip electrically connected to another terminal, and an insulation member surrounding said long clip, retained in position by said upper portion, and preventing accidental short-circuiting of said clips.

In testimony whereof I have affixed my signature.

FRANK SCORDAMAGLIA.
